[57] **CLAIM**

The ornamental design for a window attachment clip component, as shown and described.

DESCRIPTION

FIG. 1 is a top plan view of a window attachment clip component showing our new design, the bottom surface of the lower element is flat and the rounded element is uniform around the axis;

FIG. 2: is a left side elevation view of the window attachment clip component of FIG. 1, the right side elevation view being a mirror image thereof; and,

FIG. 3 is a front elevational view of the window attachment clip component housing of FIG. 1, the rear of the upright element is flat except for the rounded element.
